(57) **CLAIM**

The ornamental design for an intubation blade, as shown and described.

DESCRIPTION

FIG. 1 is a perspective view of an intubation blade in accordance with the new design;

FIG. 2 is a right side view of the intubation blade of FIG. 1; FIG. 3 is a left side view of the intubation blade of FIG. 1; FIG. 4 is a front view of the intubation blade of FIG. 1; FIG. 5 is a rear view of the intubation blade of FIG. 1; FIG. 6 is a top plan view of the intubation blade of FIG. 1; and, FIG. 7 is a bottom plan view of the intubation blade of FIG. 1.

The broken lines in the figures are directed to portions of the intubation blade that form no part of the claimed design.
